TOY CAP PISTOL OR SIMILAR ARTICLE

Frederick J. Maywald, Rutherford, N. J., assignor
to The J. & E. Stevens Sales Company, New
York, N. Y., a corporation of Delaware

Application March 9, 1953, Serial No. 23,966

Term of patent 14 years

(Cl. D34—15)

To all whom it may concern:

Be it known that I, Frederick J. Maywald, a citizen of the United States and resident of Rutherford, in the county of Bergen and State of New Jersey, have invented a new, original, and Ornamental Design for a Toy Cap Pistol or Similar Article, of which the following is a specification, reference being had to the accompanying drawing, forming a part hereof.

Fig. 1 is a top plan view of a toy cap pistol or similar article showing my new design;

Fig. 2 is a side elevational view thereof;

Fig. 3 is a front elevational view thereof, and
Fig. 4 is a rear elevational view thereof.

I claim:

The ornamental design for a toy cap pistol or similar article, as shown.

FREDERICK J. MAYWALD.
